2,206,678

MAILBOX RECEIVING DOOR

Fred Harry Shetler, Canton, Ohio

Application April 29, 1938, Serial No. 204,950

1 Claim. (Cl. 232—45)

This invention relates to improvements in mailbox receiving doors, and the object of this device is to provide the general public with a convenient and simple method of depositing letters.

Another object is to provide means for automatic closing of door-flaps upon letter deposit.

A further object is to provide means for depositing letters with one hand, leaving the other hand free to carry packages etc.

Still another object is to provide means for the depositing of letters without mutilating same.

Referring to the drawing forming part hereof,

Fig. 1 is a view in perspective of a mailbox embodying my invention.

Fig. 2 is a front plan view of Fig. 1, showing by dotted lines the construction and mounting arrangement of receiving door-flaps, the weighted arm of the upper door-flap, the connecting link between said arm and the lower door-flap, the discharge door and mounting arrangement thereof.

Fig. 3 is a vertical view through the side of the mailbox showing the arrangement of receiving door-flaps and their motivating mechanism, and the construction of the discharge door.

Referring to the drawing in detail, the body portion of the mailbox is shown at 1, the said body having a curved top portion as shown at 2, and an elliptical opening or paper receptacle at 3. The upper front portion of the mailbox has a longitudinal opening at 4, and a combination of coordinating upper and lower door-flaps at 5 and at 6 pivotally mounted to the interior front wall to close said opening as shown at 7 and at 8, and at 13 and 14 in Figs. 2 and 3.

The lower exterior central portion of the upper door-flap 5 has a cylindrical finger-tip bar integral therewith at 10, the said bar serving as a finger-tip rest for persons desiring to push open the said door-flap for letter deposits. The lower interior portion of said door-flap overlaps the upper exterior portion of the lower door-flap 6 to prevent rain from entering into the box through the said lower door-flap, the said lower door-flap having extended side portions as shown by dotted lines in Fig. 2.

When said upper and lower door-flaps are in open position, the lower horizontal portion of the upper door-flap touches the upper end portions of the said extended side portions of the lower door-flap, forming a longitudinal opening 55 between said door-flaps for letter deposits, the

lower portion of said lower door-flap having a flanged angular ledge extending exteriorly of the box, as shown in Figs. 1 and 3. The said ledge prevents rain from entering into the said box.

The interior side portion of the door-flap 5 has a weighted arm 9 attached thereto at 21, as shown in Figs. 2 and 3.

The interior side portion of the door-flap 6 has a flange attached thereto at 11, a connecting link at 12 pivotally attached to said flange and to said upper door-flap weighted arm, the said connecting link providing coordination of movement for said upper and lower door-flaps.

It is customary to hold letters in between the thumb and fingers in attempting to deposit them, and in the present instance, when the said upper door-flap is pushed inward by the fingers holding the said letters, the weighted arm of said door-flap automatically pulls the connecting link backward and the said lower door-flap inward, this inward movement of the said door-flaps exposes the longitudinal opening in between the extended side portions of the lower door-flap. The said connecting link limits the width of said opening between the lower horizontal portion of the upper door-flap and the upper horizontal portion of the lower door-flap. The thumb and the fingers simply release the said letters and they drop through the said opening into the box without mutilating same.

The said weighted arm automatically closes the said door-flaps after finger pressure is removed from said upper door-flap.

The lower front obtuse portion of the box is provided with a longitudinal opening at 15, the top portion of said opening having an inturned angular ledge at 16 which is provided with a slot for bolt engagement of a door lock. The said opening is provided with a discharge door at 17, the lower interior portion of the said door being pivotally mounted to the lower interior front portion of the box at 20 and at 21. The side portions 19 of said door are flanged inwardly to keep deposited mail upon said door and to provide pivotal support for said door, as shown at 20 in Fig. 3. The bottom portion of said door is angled inwardly and upwardly at 22, the said angled portion forcing mail to slide forward upon the door when said door is opened for the discharge of mail. The upper center portion of said door is provided with a lock at 18, the said lock engaging the slot of said inturned angular ledge.

While it is believed that from the foregoing

description the nature and advantages of the invention will be readily apparent, I desire to have it understood that I do not limit myself to the details of construction herein shown and described and that such changes may be resorted to when desired as fall within the scope of what is claimed.

I claim:

In a mailbox having a longitudinal opening in the upper front portion thereof, the combination of coordinating upper and lower door-flaps pivotally mounted to the interior front wall to close said opening, the interior side portion of the

upper door-flap having a weighted arm attached thereto, the lower exterior central portion of said upper door-flap having a cylindrical finger-tip bar integral therewith, the lower portion of said lower door-flap having a flanged angular ledge extending exteriorly of the box, and a flange attached to the interior side portion of said lower door-flap, the said flange and the upper door-flap weighted arm having a connecting link pivotally attached thereto, for the purpose 10 described.

FRED HARRY SHETLER.
